DESIGN FOR A TOY BED

Kathleen Eames Little, Salisbury, N. C.

Application August 6, 1938, Serial No. 79,169

Term of patent 7 years

To all whom it may concern:

Be it known that Kathleen Eames Little, a citizen of the United States of America, residing at Salisbury, in the county of Rowan and State of North Carolina, have invented a new, original, and ornamental Design for a Toy Bed, of which the following is a specification, reference being had to the accompanying drawing, forming a part thereof.

I claim:

The ornamental design for a toy bed, as shown.
